UNITED STATES PATENT OFFICE.

ABRAHAM PRATT, OF NEW YORK, N. Y.

DESIGN FOR A DRESS.

Application filed December 19, 1928. Serial No. 29,338. Term of patent 3½ years.

To all whom it may concern:

Be it known that I, ABRAHAM PRATT, a citizen of the United States, trading as Public Dress Company, located and doing business at 500 Seventh Avenue, in the city, county, and State of New York, have invented a new, original, and ornamental Design for a Dress, of which the following is a specification, reference being had to the accompanying drawing, forming part thereof.

looking at the front of the same with the lapel of the coat portion open;

Figure 2 is a similar front view of a dress embodying my invention showing the lapel of the coat section closed; and

I claim:

The ornamental design for a dress substantially as shown.

ABRAHAM PRATT.
